CLAIM

The ornamental design for dead front electrical connector for recharging electric vehicles, as shown and described.

DESCRIPTION

FIG. 1 is a rear perspective view of a dead front electrical connector for recharging electric vehicles showing our new design;

FIG. 2 is a right side elevational view of the electrical connector shown in FIG. 1;

FIG. 3 is a front elevational view of the electrical connector shown in FIGS. 1-2;

FIG. 4 is a rear elevational view of the electrical connector shown in FIGS. 1-3;

FIG. 5 is a top plan view of the electrical connector shown in FIGS. 1-4; and,

FIG. 6 is a bottom plan view of the electrical connector shown in FIGS. 1-5.

FIG. 1

FIG. 2

FIG. 3

FIG. 4

FIG. 5

FIG. 6
